UNITED STATES PATENT OFFICE.

RICHARD L. GILLESPIE, OF BARBERTON, OHIO, ASSIGNOR TO THE FIRESTONE TIRE AND RUBBER COMPANY, OF AKRON, OHIO, A CORPORATION OF OHIO.

PROCESS OF MAKING INNER TUBES.

Application filed January 20, 1926. Serial No. 82,464.

This invention relates to inner tubes and to methods for making the same, and particularly to the production of tubes with integral valve stems.

5 The general objects of the invention are to provide an improved inner tube construction wherein the valve is integral with the tube, to provide an improved procedure for making such tubes, and, in addition, to provide a method whereby tubes with integral 10 S-valves may be made.

The foregoing and other objects are obtained by the tube construction shown and the method illustrated in the accompanying 15 drawings, and each more fully described below. It is to be understood that the invention is not limited to the specific form thereof shown and described.

Of the accompanying drawings, 20 Figure 1 illustrates a mandrel having a tube thereon and wrapped in the manner it comes from the vulcanizer;

Figure 2 is a radial section through the tube and mandrel at the valve, showing the 25 green tube with the valve inserted therein before the wrappings have been applied;

Figure 3 is a similar view, showing the completely vulcanized tube on the mandrel after removal of the wrappings;

30 Figure 4 is a side elevation of a section of the tube at the valve, partly broken away and partly in section, and showing the removable valve plate of the mandrel which is adapted to come off with the tube as the latter is stripped from the mandrel; and

35 Figure 5 is a radial section through a completed tube at the valve.

Referring to the drawings, 10 represents a hollow mandrel, here shown of nearly 40 closed C formation, for making inner tubes of large sizes, but which may be a straight pole such as is employed in making tubes of smaller sizes. The mandrel 10 has therein on its inner periphery a circumferentially 45 elongated slot as shown at 11 in which seats a removable closure plate 12 having an aperture 13 therein, through which an inner tube valve may project.

The tube is shown at 14 and is formed of 50 raw vulcanizable rubber in any known manner and applied to the mandrel 10, closure plate 12 being in place thereon. A valve aperture is punched through the tube overlying aperture 13 and a valve reinforcing 55 patch 15 is applied to the tube.

The valve, indicated by the numeral 16, is provided with a mushroom shaped base 17 and may be either straight or S-shape, as shown. In making tubes with S-shaped valves, it has been found desirable to provide valves initially formed with only one bend therein, as indicated in Figures 1 to 4, and to bend the valve into S-shape subsequent to vulcanization. The base of valve 16 is suitably treated as with a thin coating of 60 rubber cement 18 whereby it is adapted to vulcanize to the tube. The valve 16 is then inserted into the tube through the aperture 13 on the mandrel into the position shown in Figure 2.

Pressure on the tube during vulcanization is obtained by wrapping the same with a narrow strip of fabric 19 wound helically thereon. The tube is so wrapped and together with others is inserted into a suitable 70 heater where it is vulcanized. Vulcanization of the tube under pressure of the wrapper 19 causes the base 17 to become embedded in the tube as shown in Figure 3, and the cement 18 permanently and integrally secures 80 the valve to the tube by vulcanization.

After vulcanization, the wrapper 19 is removed and the tube stripped from the mandrel, this latter step being accomplished in the customary manner, the tube being turned 85 inside out. Thus the smooth surface of the tube vulcanized against the mandrel will be on the outside of the completed tube.

In stripping the tube, closure plate 12 will come off the mandrel therewith and the valve 16 will be drawn outwardly through slot 11 (see Figure 4). Plate 12 may then be withdrawn from the tube and replaced in slot 11. The valve 16 is given an additional bend to form it to the desired S-shape as shown in 95 Figure 5 and the ends of the tube are spliced together and vulcanized to complete the tube in a known manner.

It will appear from the foregoing that a tube has been provided which will be absolutely leak-proof at the valve and which requires no threaded valve stem or nuts and clamps to secure the valve in the tube. The mushroom-shaped base 17 on the valve 16 is such as to assume the general shape of the 100 outer surface of the tube during vulcanization (Figure 3) whereby a flat surface is avoided, pressure of the wrapper 19 thereon being equalized over its bottom convex surface, thus insuring that the valve is properly 110

embedded in the tube, the rubber flowing about the outer edge of the base (Figure 3) to securely interlock the base within the wall of the tube.

5 Modifications of the invention may be resorted to without departing from the spirit thereof or the scope of the appended claims.

What is claimed is:

1. The process of making inner tubes with 10 **S** valves, said process comprising providing a valve with a base and having a single bend therein, inserting the valve in a tube during the preliminary shaping of the latter, molding and vulcanizing the tube so as to embed 15 the base of the valve in the wall thereof and finally bending said valve to **S** shape by forming a second bend therein.

2. The process of making inner tubes with **S** valves, said process comprising providing

a valve with a base and having a single bend 20 therein, treating said base so that it will vulcanize to the soft rubber of the tube, inserting the valve in the tube during the preliminary shaping of the latter, molding and vulcanizing the tube so as to embed the base of 25 the valve in the wall thereof and vulcanize it to the rubber thereon, and finally bending said valve to **S** shape.

3. The process of making inner tubes with 30 **S** valves, said process comprising providing a valve with a base, inserting the valve in the tube during the preliminary shaping of the latter, molding and vulcanizing the tube so as to embed the base of the valve in the 35 wall thereof, and finally bending said valve to **S** shape.

RICHARD L. GILLESPIE.
